UNITED STATES PATENT OFFICE.

CHASE COLVIN, OF SOUTH CHARLESTON, OHIO.

FENCE-POST.

SPECIFICATION forming part of Letters Patent No. 759,968, dated May 17, 1904.

Application filed January 12, 1903. Serial No. 138,740. (No model.)

To all whom it may concern:

Be it known that I, CHASE COLVIN, a citizen of the United States, residing at South Charleston, in the county of Clark and State of Ohio, 5 have invented certain new and useful Improvements in Fence-Posts, of which the following is a specification, reference being had therein to the accompanying drawings.

This invention relates to improvements in 10 fence-posts, and more particularly to terminal posts for wire fences under tension, and has for its object to provide a simple, strong, and durable post adapted to effectively resist the pull of the fence-wires upon it when in use, 15 and thus maintain an upright position.

To these ends my invention consists in certain novel features, which I will now proceed to describe and will then particularly point out in the claims.

20 In the accompanying drawings, Figure 1 is a perspective view of a fence-post embodying my invention. Fig. 2 is a plan section taken on the line $\alpha\alpha$ of Fig. 1 and looking in the direction of the arrows. Fig. 3 is a detail 25 sectional view taken on the line $\gamma\gamma$ of Fig. 1 and looking in the direction of the arrows; and Fig. 4 is a detail view, in side elevation, of a portion of the base.

In the said drawings, 1 indicates the body 30 of the post, which is composed of two angle-bars 2. These angle-bars are so arranged that two of their flanges (indicated by the reference-numeral 3) are parallel and extend in the general direction of the fence, while the 35 other two flanges 4 lie in the same transverse plane, but extend in opposite directions. The angle-bars are spaced apart by sleeves or thimbles 5 and are connected by bolts 6. The description just given applies to the body of 40 the post, or, in other words, that portion of the post which is above ground when the post is in position. Below the ground the two angle-bars diverge outwardly and downwardly, as shown in Fig. 1, so as to brace the 45 post laterally, and their lower ends are attached to a base or support, (indicated as a whole by the reference numeral 7,) which base or support is buried in the ground a suitable distance below the surface of the soil. The form 50 which I prefer for this base or support is that

shown, in which it, like the post, is constructed entirely of angle-bars. It comprises a cross-piece 8, having a horizontal flange or member 9 and a vertical flange or member 10. The lower ends of the angle-bars 2 are secured to 55 the horizontal flange 9 by cutting away a portion of the flange 4 and bending out the projecting end of the flange 3, so as to rest upon the top of the flange 9, as indicated at 11, the two parts being connected by a bolt 12. It 60 will be observed that the flanges 4 of the post angle-bars seat against the flange 10 of the cross-piece, so as to be supported by these latter, thus making a firm joint. The base or support 7 also comprises an angle-bar 13, 65 bent into approximately V shape and comprising a horizontal flange 14 and a vertical flange 15. The ends of the flange 15 are cut away so as to permit the projecting portions of the horizontal flange 14 to be extended underneat the cross-piece 8, to which they are secured by the same bolts 12 which fasten the feet of the post to said cross-piece on the upper side thereof.

The post is additionally connected with the 75 base by means of a tension-brace 16, which extends from the apex of the base to the lower end of the body of the post proper where it emerges from the ground. This brace serves to strengthen the post against the pull of the 80 fence and is made adjustable, so as to compensate therefor and insure an upright position of the post relatively to the base. To this end the brace 16 may be threaded at either or both of its ends to receive an adjusting-nut 85 which bears against a suitable abutment. In the present instance I have shown the brace as thus provided with adjusting devices at each end. The lower end of the brace 16 passes through an aperture in the vertical 90 flange 15 of the base member 13, at the apex thereof, and is threaded, as indicated at 17, per end the brace 16 passes between the two to receive an adjusting-nut 18. At its upper end the brace 16 passes through an abutment-plate 95 19 in front of the same, its end being threaded, as indicated at 20, to receive an adjusting-nut 21, which bears against the abutment-plate 19. In this way the brace may be tensioned from either end before the post is 100

placed in position in the ground and may be tensioned at its upper end after the post is thus placed in position.

In order to provide means in addition to the base 7 for enabling the post to withstand the pull of the fence, I employ a thrust-brace (indicated as a whole by the reference-numeral 22) bearing at its lower end against a suitable abutment on the ground and at its upper end against the body of the post a considerable distance above the surface of the ground. The ground-abutment is indicated at dotted lines at 24 and may be a stone or other suitable device for the purpose. This thrust-brace consists of two angle-bars 25, spaced apart at their lower ends by means of a thimble 26 and connected by a bolt 27. Their upper ends receive between them the flanges 3 of the post, against the sides of which the vertical flanges 28 of the thrust-brace rest. The horizontal flanges 29 of the thrust-brace bear against the flanges 4 of the post. The bolt 30 passes through the flanges 3 of the post and through slots or enlarged holes 31 in the flanges 28 of the thrust-brace. In this way the greater portion of the strain is taken from the bolt 30 and is transmitted from the thrust-brace directly to the flanges 4 of the post.

The lower end of the thrust-brace is connected with the lower end of the body of the post by means of a tensioning device 32, consisting, preferably, of a wire rope having one end looped around the thimble 26 of the bolt 27, while its other end is connected to an eye-bolt 33, which passes between the angle-bars 2 of the post slightly above the surface of the soil and also through an abutment-plate 34 at the rear of the same, the threaded rear end of the eyebolt receiving an adjusting-nut 35, 40 by means of which the member 32 may be tensioned in an obvious manner.

The fence-wires, (indicated at 36,) pass between the two angle-bars of which the thrust-brace is composed and also between the two angle-bars of which the body of the post is composed and are alternately wrapped around said last-mentioned bars, so as to equalize the strain.

It will be observed that the post is of simple and strong construction, and therefore inexpensive and durable, while provision is made for varying the tension connection between the post and its base and also between the post and the thrust-brace, these tensioning provisions being independent in their operation. It will also be observed that in its preferred form the post is constructed almost entirely of angle-bars, the same being a commercial form of iron readily obtainable and so disposed as to give great strength to the post. The parts of other form are merely the spacing-thimbles, connecting-bolts, and tensioning devices. It will be further noted that the base when constructed of angle-bars in the manner described presents an effective re-

sistance to strains which tend to move it either vertically upward or laterally through the soil in the direction of the pull of the fence. This arises from the fact that the angle-bars present their horizontal flanges to resist the upward pull, while their vertical flanges resist the horizontal pull. It will also be noted that the angle-bars of which the base is composed are so arranged that their horizontal flanges or portions extend from their junction with the vertical portions in the direction of the pull or strain upon the post, so that any tendency of the post to move in this direction will result in thrusting these horizontal portions under the superimposed soil in such a way as to always maintain a mass of soil above said horizontal flanges, thus preventing their upward movement. If the horizontal flanges projected in the opposite direction, any forward movement of the post would tend to remove the soil from above the horizontal flanges and would diminish their capability of resisting upward movement of the post. It will also be seen that the connection between the upper end of the thrust-brace and the post-body is such that while it leaves sufficient play to permit the end of the brace to abut against the post-body, and thus relieve the connecting-bolt of strain, it holds these parts together in such a way that they cannot be separated to an extent sufficient to prevent their coming to a proper bearing whenever subjected to the strains which they are intended to meet in practical use. The vertical flange 10 of the cross-piece 9 is presented directly across the line of pull of the fence, while the vertical flange 15 of the V-shaped member 13 effectually resists the horizontal pull by reason of the soil wedging in between its convergent parts.

I do not wish to be understood as limiting myself strictly to the precise details of construction hereinbefore described, and shown in the accompanying drawings, as these details may obviously be modified without departing from the principle of my invention.

Having thus fully described my invention, what I claim as new, and desire to secure by Letters Patent, is—

1. A terminal post for wire fences, comprising a body portion composed of angle-bars provided with means for spacing apart and uniting them and having their lower portions diverging below the ground, and a triangular base composed of angle-bars arranged with their flanges horizontally and vertically, to respectively resist upward and lateral strains, the lower ends of the post-body being secured to one of the sides of the base, which side is arranged transversely to the plane of the fence, and the two remaining sides converging away from the first-mentioned side in a direction opposite to the direction of the lateral strain on the post, the horizontal flanges of the angle-bars of which the base is composed ex-

tending from the vertical flanges in the direction of the strain on the post, substantially as described.

2. A terminal post for wire fences, comprising a body portion composed of angle-bars having two of their flanges parallel with the plane of the fence, and the remaining two flanges at right angles thereto, in combination with a thrust-brace composed of two parallel angle-bars having two of their flanges parallel and in vertical planes and slotted longitudinally at their upper ends, the remaining two flanges of the braces lying in the same plane and bearing against the transverse flanges of the bars composing the post-body,

a bolt passing through the slots in the upper ends of the thrust-brace and through apertures in the parallel flanges of the post-body, which flanges are embraced between the parallel flanges of the brace members, and a tensioning device connecting the lower end of the thrust-brace with the post-body, substantially as described.

In testimony whereof I affix my signature in presence of two witnesses.

CHASE COLVIN.
